UNITED STATES PATENT OFFICE.

ASA H. BALLARD, OF FORT MORGAN, COLORADO.

BEET-TOPPER.

1,344,849.

Specification of Letters Patent. Patented June 29, 1920.

Application filed June 23, 1919. Serial No. 306,169.

To all whom it may concern:

Be it known that I, ASA H. BALLARD, a citizen of the United States, residing at Fort Morgan, county of Morgan, and State 5 of Colorado, have invented certain new and useful Improvements in Beet-Toppers; and I do declare the following to be a full, clear, and exact description of the invention, such as will enable others skilled in the art to 10 which it appertains to make and use the same, reference being had to the accompanying drawings, and to the characters of reference marked thereon, which form a part of this specification.

15 This invention relates to devices used in harvesting beets, and particularly to a device for stopping the beets and loading them.

The object of the invention is to shorten 20 the ordinary process of handling beets in the field, and is designed to eliminate the several movements of hand labor which consist, after lifting the beets, of obtaining a hold to present the top to be cut, of cutting 25 off the top with a knife, throwing the beets in a pile and subsequently loading them by hand. With the present invention, the beets, after being pulled, are merely lifted and placed in position on the machine. The 30 machine then automatically carries them past a cutter, cuts off the tops and discharges them into a wagon or other suitable receptacle.

Briefly, the invention comprises a truck, 35 having a framework carrying endless conveyers provided with pockets to receive the beets, means to move said conveyers, knives reciprocating in synchronism with the conveyers, means to reciprocate the knives to 40 remove the tops, and means to hold the beets while the knives are removing the tops.

In the drawing:

Figure 1 is a side elevation of the improvement;

45 Fig. 2 is a plan thereof;

Fig. 3 is a fragmentary detail elevation, taken from the line 3-3 of Fig. 2;

Fig. 4 is a fragmentary detail end elevation, showing the beet-engaging and cutting 50 means, and is taken from the line 4-4 of Fig. 3;

Fig. 5 is a further detail, showing the beet-holding means, taken on the line 5-5 of Fig. 4.

55 A truck framework 10 is provided with low wheels 12, positioned beneath the frame-

work, the frame carrying a plurality of drums 14, journaled at 15, over which drums endless chain conveyers 16 pass. The chain conveyers 16 are provided with blocks 18, 60 cut out at the sides and slightly spaced on the chain 16, as indicated at 19, whereby dirt may fall through the chain, the shape of the blocks providing pockets 20 therebetween, in which the beets B are received. 65

An engine 22 or other suitable means for providing power is mounted upon the framework and is provided with flywheels 24, and a gear 26, over which a chain 28 passes, a sprocket 30 being mounted upon a shaft 32, 70 journaled in standards 33. The shaft 32 carries another sprocket 34, over which passes a chain 36, extending to a sprocket 38 mounted on a shaft 40, carrying the drums 14 at one end of the machine. The 75 drums 14 at the opposite end of the machine receive power by means of sprocket 42, mounted on shaft 40, over which the endless chain 44 extends, the latter engaging gear 46, mounted on shaft 48, at the 80 opposite end of the machine and upon which the drums 14 at said opposite end are mounted.

An eccentric 50 is connected with the shaft 32 and suitably geared down by any means 85 (not shown), the eccentric 50 being provided with a pitman 52 connected with a vertically reciprocating rod 54, passing through guide sleeve 56 on bracket 58, which is connected with one of the standards 33. The 90 lower end of the rod 54 is provided with a knife 60. A second guide sleeve 62 is provided on bracket 58, and through this sleeve a vertically disposed rod 64 passes the lower end of said rod 64, being forked at 66 to 95 engage the beets during the cutting operation. The upper end of the rod 64 is reduced, as shown at 68, and about this reduced portion a spring 70 is mounted, the lower end of which engages the shoulder 72 100 of the rod, the upper end being engaged by an arm 74, projecting from the reciprocating knife-carrying rod 54.

The arm 74 is retained in engagement with the spring 70 by means of nut 76, provided on the upper end of reduced portion 68.

In using the machine, a few rows of beets are first pulled on each side of the machine, the machine being drawn up between the 110 rows. The beets are lifted by hand and placed in the pockets 20 upon the conveyers

16. As the beets are carried past the knife 60, the latter reciprocates to remove the tops. The reciprocation of the knife 60 is so timed that it takes place as each pocket passes the 5 knife. As the rod 54, which carries the knife 60, falls, the arm 74 engaging the spring 70 forces down the rod 64 and fork 66 into engagement with the tip of the beet. The spring 70, however, is weak enough to 10 yield under the pressure of the arm 74 after the fork 66 engages the beet, so that the arm 74 can continue its downward movement with the knife 60 to remove the top of the beet. In this manner, rocking of the 15 beet in the pocket 20 is prevented during the cutting operation. After the top has been removed, the knife 60 is elevated, carrying with it the arm 74, which engages the nut 76 in its upward movement, thereby also 20 elevating the rod 64 and withdrawing it from the pocket 20. The beets, after being topped, are discharged into a wagon or other receptacle.

I claim:

25 1. In a beet-topping device, a conveyer having pockets thereon adapted to receive the beets, a knife arranged to reciprocate in synchronism with the movement of said conveyer to remove the tops as the pockets 30 pass the knife, a rod upon which said knife is mounted, a reciprocating rod movable in conjunction with said knife-carrying rod and having means to engage the beets dur-

ing the cutting operation, and a connection between said rods whereby the latter are 35 movable together.

2. In a beet-topping device, a conveyer having pockets thereon adapted to receive the beets, a knife arranged to reciprocate in synchronism with the movement of said conveyer to remove the tops as the pockets pass the knife, a rod upon which said knife is mounted, a reciprocating rod movable in conjunction with said knife-carrying rod and having means to engage the beets during the cutting operation, and a connection between said rods whereby the latter are 40 movable together, said means comprising a spring mounted upon the rod carrying said beet-engaging means and an arm projecting 45 from said knife-carrying rod and engaging said spring.

3. In a beet-topping device, a conveyer having pockets thereon adapted to receive the beets, a knife arranged to reciprocate in synchronism with the movement of said conveyer to remove the tops as the pockets pass the knife, a rod upon which said knife is mounted, a reciprocating rod movable in conjunction with said knife-carrying rod, 50 and having means to engage the beets during the cutting operation, and means for moving the two rods together.

In testimony whereof I affix my signature.

ASA H. BALLARD.
